UNITED STATES PATENT OFFICE.

DAVID H. LENTZ, OF CHICAGO, ILLINOIS, ASSIGNOR TO SELLERS MANUFACTURING COMPANY, OF CHICAGO, ILLINOIS, A CORPORATION OF ILLINOIS.

COMPOSITE ROLL FOR ROLLING METAL.

983,828.

Specification of Letters Patent.

Patented Feb. 7, 1911.

Application filed December 20, 1909. Serial No. 533,984.

To all whom it may concern:

Be it known that I, DAVID H. LENTZ, a citizen of the United States, residing at Chicago, in the county of Cook and State of Illinois, have invented certain new and useful Improvements in Composite Rolls for Rolling Metal, of which the following is a specification.

My invention relates to a composite roll for rolling metal in which the body or main portion of the roll is made of relatively cheap iron or low carbon steel, but which is provided with a hard or high steel member which affords the rolling surface. A roll of this sort may be employed to perform various sorts of work, and is particularly suitable in the manufacture of railroad tie or wear plates.

The rolls employed in making tie or wear plates are subjected to very great strains, particularly because it is necessary to form such articles with upstanding projections or ribs, and, in order that the plates should best resist the particular strains to which they are subject, they should be rolled so that these ribs or projections are at right angles to the grain of the plate, that is, to the direction of the rolling. If rolls made of soft iron are employed, the strains to which they are subjected very soon cause them to be worn, to the extent of making them useless, or impairing their proper operation. It is not practical on the other hand to make the rolls entirely of hard or high carbon steel, both because of the expense involved and also because of the difficulty of shaping the roll entirely out of this very hard metal. Furthermore, it is desirable that the part of the structure affording the rolling surface should be removable, because, if such is the case, the fashioning of the rolling surface to give it the desired contour and pattern is facilitated. I have, therefore, proposed to construct a roll for the manufacture of tie plates, or for similar rolling operations, in which a high carbon steel collar is securely but removably mounted upon a soft steel or iron body part, and two alternate constructions for a roll of this character have been shown and described in my application, Serial No. 531471, filed December 4, 1909.

The present invention relates to a construction of composite roll different from

those shown in the above application, and its object is to overcome the difficulty which arises when it is attempted to secure the hard steel collar directly to the shaft of the roll. In such case it is, of course, necessary that the internal diameter of the collar should be precisely that of the shaft to which it is to be fitted. This involves a machining of one or both of the contacting surfaces. The difficulty is enhanced when, as is customary, the hard steel ring is tempered after the pattern is cut upon the surface, because such tempering often results in some shrinkage or distortion of the collar, which, however slight it may be, affects the fit between the collar and the shaft of the roll.

My present invention contemplates initially making the internal diameter of the collar greater than the diameter of the part of the roll upon which the collar is fitted, and interposing between the collar and the roll a wedge member which may be given any adjustment necessary to produce a close fit between the collar and the roll. It will be seen that this construction is considerably simpler in several respects than the constructions described in my application above referred to.

The invention is illustrated in a preferred embodiment in the accompanying drawings, wherein—

Figure 1 is a side elevation of a pair of tie-plate forming rolls, the lower of the two rolls being shown in section; and Fig. 2 is a section taken on line 2—2 of Fig. 1.

Like characters of reference indicate like parts in the several figures of the drawings.

Referring to the drawings, A represents the soft iron body part of the lower roll, which roll will be first described. The roll is formed with the preferably integral boss B having the groove B'; with the shaft C having the threaded part D; and with the journal forming portions E, E. Preferably the roll has the centrally enlarged bore F for the introduction of water for cooling purposes.

The hard or high carbon steel collar G is formed preferably with the tapered internal surface G'. The least internal diameter of the collar is greater than the diameter of the shaft portion C of the soft iron body part. The outer or rolling surface of the collar may be formed with any

desired pattern, such as that shown at G². The collar abuts at one side against the boss B and on the other side an annular member H is provided which can be forced 5 against the collar by means of the nut J, preferably provided with the grooves J' for a spanner.

Interposed between the collar G and the shaft C is a wedge member which is shown 10 as consisting of a split ring K having a tapered outer surface, the split in the ring being shown at K'. Screws L are threaded through the boss B and engage the split ring K, these screws having the lock nuts 15 L'. By this means the split ring may be driven between the collar and the shaft C with any amount of force necessary to obtain a secure engagement between the collar and the body of the roll. If there is no 20 looseness between these parts, there will be no opportunity for wear, but if it should happen that the parts should become loose and the engaging surfaces worn down, the collar may be tightened up on the roll by 25 further adjustment of the screws L.

The upper roll M may be in all respects the same in construction as the lower roll A just described, except that the integral boss N is provided with a rib N' instead of 30 a groove, this rib fitting into the groove B' of the lower roll; the purpose of this being to prevent any endwise movement between the rolls; also the annular member H' is 35 of smaller diameter than the member H, and, in the particular arrangement shown, the hard steel collar O on the upper roll has its rolling surface provided with a different pattern formed, namely, by the notches or grooves O'. In a composite 40 roll of this character the strains as between the collar and the spindle or shaft of the roll are great, and as a result any looseness between these parts is likely to be injurious to or destructive of the soft iron or steel 45 shaft or spindle. By driving the wedge between the collar and the shaft on which it is mounted, the collar is given a firm bearing on the shaft, which can be tightened when necessary, so that the strains 50 exerted on the rolling surface of the collar are transmitted directly to the shaft on radial lines. Preferably, the wedge has a very slight taper and is practically the width of the collar, as shown, the wedge 55 being just enough narrower than the collar to give room for driving it, if necessary. It will be seen that a closed pass is formed in the lower roll by means of the boss B and annular clamping member H, the collar O on the upper roll forming a tongue 60 which extends into the groove so formed in the lower roll. This feature of the invention is not claimed herein as it is claimed in my co-pending application above referred to. Obviously, if desired, one or other of 65

the rolls might be an iron or soft steel roll of the old type, or might be of any other construction. That is, it is not essential that both rolls should be of identical construction.

As modifications in shape, form and construction of the parts will readily suggest themselves to those familiar with this art, I do not limit myself to the details of form and construction shown and described except so far as the scope of any of the claims demands.

I claim:

1. A metal working roll comprising a body part of relatively soft iron or steel, 80 a member of high carbon steel provided with a metal forming surface, and a wedge which is interposed between the high carbon steel member and the iron or steel body part, so as to transmit the strains exerted 85 against said metal forming surface directly to the portion of the body part inwardly thereof.

2. A metal working roll comprising a body part, a collar provided with a metal forming surface, and a wedge which is interposed between the inner face of the collar and the body part so as to transmit the strains exerted against said metal forming surface directly to the portion of the 95 body part inwardly thereof.

3. A metal working roll comprising a body part, a collar, and a wedge ring interposed between the inner face of the collar and the body part so as to transmit 100 the strains exerted against said metal forming surface directly to the portion of the body part inwardly thereof.

4. A metal working roll comprising a body part, a collar having its inner surface 105 tapered from one side of the collar to the other and provided with a metal forming outer surface; and a wedge ring substantially the width of said collar interposed between the collar and the body, for 110 the purpose described.

5. A metal working roll comprising a body part, a collar provided with a metal forming outer surface, and a split wedge ring interposed between the inner face of 115 the collar and the body part so as to transmit the strains exerted against said metal forming surface directly to the portion of the body part inwardly thereof.

6. A metal working roll comprising a body 120 part, formed with a shaft, a collar provided with a metal forming outer surface arranged on said shaft, means on said body part abutting against the collar on each side, and a wedge ring interposed between the shaft and 125 the collar, for the purpose described.

7. A metal working roll comprising a body part formed with a shaft and with an integral boss, a collar surrounding said shaft and abutting against said boss, a wedge ring 130

interposed between said collar and said shaft, and removable means on the other side of the collar from the boss which bears against the collar for securing the collar 5 on the shaft.

8. A metal working roll comprising a body part formed with a shaft and with an integral boss, a collar surrounding said shaft and abutting against said boss, a wedge ring 10 interposed between said collar and said shaft, and removable means on the other side of the collar from the boss which bears against the collar for securing the collar on the shaft, comprising an annular member 15 and a nut.

9. A metal working roll comprising a body part formed with a shaft, a collar provided with a metal forming outer surface arranged on said shaft, clamping members which bear 20 against the collar on each side thereof, and a wedge ring between said clamping members and interposed between the shaft and the collar.

10. A metal working roll comprising a body part formed with a shaft, a collar provided with a metal forming outer surface arranged on said shaft, clamping members which bear against the collar on each side thereof, a wedge ring between said clamping 30 members and interposed between the shaft and the collar, and means for moving said wedge lengthwise of the shaft so as to tighten the engagement between the collar and the shaft.

35 11. A metal working roll comprising a body part formed with a shaft, a collar provided with a metal forming outer surface arranged on said shaft, clamping members which engage the collar on each side thereof, a wedge ring between said clamping 40 members and interposed between the shaft and the collar, and screws extending through

one of said clamping members which bear against said wedge ring whereby said ring may be moved lengthwise of the shaft to 45 tighten the engagement between the collar and said shaft.

12. A metal working roll comprising a body part formed with a shaft and with an integral boss, a collar surrounding said shaft and abutting against said boss, a wedge ring interposed between the collar and the shaft, a clamping member on the other side of the collar from the boss, and means other than said clamping member whereby said 55 wedge ring may be moved lengthwise of the shaft so as to tighten the engagement between the collar and said shaft.

13. A metal working roll comprising a body part formed with a shaft and with an 60 integral boss, a collar surrounding said shaft and abutting against said boss, a wedge ring interposed between said collar and said shaft, a clamping member on the other side of said collar from said boss, and screws which 65 extend through said boss and engage said wedge ring for the purpose described.

14. A metal working roll comprising a shaft, an annular member on said shaft provided with a metal forming outer surface, 70 the inner diameter of said annular member being greater than the diameter of the shaft and its inner surface being tapered, a wedge ring which is interposed in the annular space 75 between said annular member and said shaft, said wedge and annular member having a very slight taper so that the strains exerted against the annular member are transmitted directly to said shaft.
